UNITED STATES PATENT OFFICE

2,508,658

RAILWAY BRAKE BEAM STRUCTURE

Harry M. Van Sweringen, Chicago, Ill., assignor
to Chicago Railway Equipment Company, Chi-
cago, Ill., a corporation of Illinois

Application July 22, 1946, Serial No. 685,321

1 Claim. (Cl. 188—224.1)

1

The invention relates to railway brake beams of the truss type and consists in structure for maintaining the assembly of the compression member, the tension member and the brake head.

In the usual truss type brake beam, the head is seated on the end of the compression member and has a bearing on its outer face for a nut threaded on the end of the tension rod which passes through the brake head. If the nut works off or if the tension rod fails, the head may become disassembled from the compression and tension members. In such event, if the only support for the beam is the usual swing hanger received in the head, the beam may fall to the track and may cause serious damage to the truck and even cause a wreck.

The main object of the invention is to maintain assembly of the beam parts in the event the tension rod or the nut fails.

It is a further object of the invention to provide a safety retainer for the head and other beam members which is simple, inexpensive and effective for the purposes indicated.

It is a further object to attain this result without appreciably weakening the beam compression member, tension member or brake head.

Another object is to provide an easily removable safety retainer in the event the brake beam must be disassembled for making repairs.

These and other detail objects are attained by which the structure illustrated in the accompanying drawings, in which:

Figure 1 is a top view of a railway truss type brake beam embodying one form of the invention, the right hand end being sectioned and showing the parts as the safety retainer is being applied.

Figure 2 is a detail vertical view looking in the direction of the arrow 2 in Figure 1, showing the safety retainer applied, and drawn to an enlarged scale.

Figure 3 is a section corresponding to the right hand end of Figure 1, showing the safety retainer applied, and drawn to an enlarged scale.

Figure 4 is a transverse vertical section taken approximately on line 4—4 of Figure 2.

Figure 5 is a view similar to Figure 2 showing another form of the invention.

Figure 6 is a top view corresponding to the right hand end of Figure 1, drawn to an enlarged scale, and showing the embodiment of Figure 5, and

Figure 7 is a transverse vertical section taken approximately on line 7—7 of Figure 5.

The beam illustrated in Figures 1—4 includes 55

2

a channel-shaped compression member 1, a round rod tension member 2, a strut 3 intermediate the ends of the beam, brake heads 4 mounted on the converging ends of the compression and tension members, and tensioning nuts 5 threaded on the ends of the tension member. Each head 4 includes the usual elements 6 facing forwardly of the beam to support the usual brake shoe (not shown). The outer side 7 of the head has a bearing 8 for nut 5. The inner side 9 of the head preferably includes a sleeve 10 which encircles tension rod 2 and restrains tension rod 2 against play relative to compression member 1. The head is recessed inwardly from its inner side 9 to receive the end portion of compression member 1 and the end of the latter is seated at 11.

All of the above described features correspond to well known structure. A flange 13 extends rearwardly from brake head sleeve 10 and has portion 13a extending parallel to compression member 1. The web of compression member 1, head back wall 12 and portion 13a of flange 13 are provided with aligned apertures 14 adjacent sleeve 10. After brake head 4 is assembled with compression and tension members 1 and 2, a tapered pin 15 having a head 16 at one end is inserted in apertures 14 (Figure 1), and is forced into engagement with sleeve 10 so that the opposite end 17 of the pin bends sufficiently to prevent the pin withdrawing from apertures 14. Preferably pin 15 fits loosely in apertures 14 so that during normal operation of the brake beam structure, there is no load or stress on the pin. The pin functions upon removal of tensioning nut 5 to maintain assembly of compression member 1, tension rod 2 and brake head 3.

The structure shown in Figures 5, 6 and 7 resembles that described above, except that apertures 20 for a plurality of vertically disposed retaining pins 28 are formed in the top and bottom flanges 21 and 22 of the beam compression member 23 and in the top and bottom walls 24 and 25 of the compression member receiving pocket 26 in brake head 27. When pins 28 are driven home, they are distorted by engagement with sleeve 29 of brake head 27 similar to the distortion of pin 15 as described above.

The safety retainers here illustrated are not intended to take the place of the tensioning nuts for resisting the thrusts exerted longitudinally of the beam when the brakes are applied and released but they will prevent the head from being disassembled accidentally from the remaining beam parts and the resultant dropping of the parts to the rail.

Details of the construction may be varied substantially without departing from the spirit of the invention and the exclusive use of modifications coming within the scope of the claim is contemplated.

What is claimed is:

In a railway truss type brake beam including a channel-like compression member and a tension rod with their end portions converging, a brake head member receiving said end portions and having a back wall engaging the outer face of the web of said compression member and having a sleeve spaced from said wall and receiving said tension rod and also having a flange extending rearwardly from said sleeve and including a portion extending parallel to said compression member, there being aligned apertures through the web of said compression member

and the back wall of said head member and said flange portion, and a pin extending through said apertures to prevent accidental disassembly of said members.

H. M. VAN SWERINGEN.
